UNITED STATES PATENT OFFICE

ROBERT J. STEPHENSON, OF AUBURN, NEW YORK, ASSIGNOR TO STEPHENSON PROTECTAHOOD CORPORATION, OF AUBURN, NEW YORK, A CORPORATION OF NEW YORK

LINING FOR AUTOMOBILE HOODS

Application filed April 10, 1925. Serial No. 22,185.

This invention relates to linings for the hoods of automobiles for confining the heat within the hood and also for protecting the paint and finish on the outside of the hood from injury by the heat within the hood, and it has for its object a particularly simple and efficient lining construction by which the lining is readily applied to the hood.

I am aware that it has been proposed, heretofore, to fasten heat insulation linings inside of motor vehicle hoods but such linings were either permanently fastened in place, as by means of cement or rivets, or detachably connected to the hood by clamps or brackets fastened to the hood and receiving the insulating lining or by loose and separable clamps. Such linings are objectionable from the commercial standpoint. The fastening of the lining in position by cement or rivets prevents the removal of the lining, or a part thereof, in warm weather, a thing which is often desirable in order to permit the free circulation of air around the motor. Furthermore, this renders the application of the lining to the hood an expensive and slow process, requiring special tools and equipment, and, for that reason, it has not been commercially practicable for accessory dealers to handle such linings. The same objections apply to constructions in which the structure of the hood is modified as by providing brackets or clamps attached to the hood for receiving the lining. Loose or separable clamps are objectionable because of the time required in applying them and because they are apt to work loose and also because they disfigure the automobile.

One object of my invention is to provide an insulating lining for application to motor vehicle hoods which is self-contained in that it carries fastening devices cooperative with the hood for detachably securing the lining in position adjacent the inner surface of the hood, whereby the lining can be applied quickly and easily and no modification of the structure of the hood is required for its application. A further object is to provide a construction such that the lining is detachable and, if made in sections, one of the sections may be detached leaving the other in

position and if desired one section can be hinged with reference to the other so as not to interfere with the hinging movement of the hood sections.

The invention consists in the novel features and in the combinations and constructions hereinafter set forth and claimed.

In describing this invention, reference is had to the accompanying drawings in which like characters designate corresponding parts in all the views.

Figure 1 is a fragmentary face view partly broken away of the top section of a lining embodying my invention.

Figure 2 is a fragmentary face view of the side section thereof.

Figure 3 is an enlarged detail view of another form of adjustable clip for attaching the top sections.

Figure 4 is a sectional view of a hood with the lining shown in Figures 1 and 2 attached.

Figure 5 is an enlarged fragmentary sectional view of a hood with the top section attached having the clip shown in Figure 3.

Figure 6 is a detail sectional view of the lower edge of the top section of the hood shown in Figure 5 with the lining attached thereto.

This invention comprises a lining for automobile hoods and is provided with means for securing or attaching the lining at its upper and lower edges to the hood and detachably hinging sections of the lining together at the hinge joint between the top and side sections of the hood. The lining itself may be of any suitable form, size and construction or of the construction shown in my pending application Sr. No. 525,921, filed December 30, 1921, it consisting of sheets of felt, asbestos and wire mesh cloth 1, 2, 3, these layers being secured together in any suitable manner as by enclosing the edges thereof in a binder or hem 4 and securing the hem in position by rivets or by stitching. The felt layer 1 lies adjacent the hood and the asbestos layer 2 is interposed between the wire mesh 3 and the felt layer 1. The wire mesh is a heat deflector, the asbestos a heat insulator and the felt a sound deadener.

Automobile hoods usually comprise top

and side sections 5, 6, the top sections 5 being hinged to a rod 7 at their tops and the side sections 6 being hinged at 8 to the top sections.

5 In some hoods as seen in Figure 4, the top sections 5 are formed with downturned flanges 13 at their hinged edges which are attached to hinge leaves 14 on the hinge pin 7, or as seen in Figure 5, the top sections are 10 formed with backwardly turned flanges 15 and the sections secured to hinge leaves 16.

The lining includes sections 17, 18 underlying the top and side sections 5, 6 of the hood. Each of the sections 17 of the lining 15 is provided with clips 19 at their edges arranged to interlock or coat with the flanges 13 or 15.

When the lining is to be used with a hood having the flanges 13, Figure 4, the clips are 20 formed with downturned flanges 20 which coat with or abut against the flanges 13 and are secured thereto in any suitable manner as by screws and nuts 21 and 22.

When a lining is used with a hood of the 25 construction shown in Figure 5 having the flange 15, the flanges 23 of the clips are straight and the clips are inserted between the flanges 15 and the main body of the top section of the hood. These clips are connected to the lining sections 17, by sliding or 30 adjustable connections for the purpose of projecting the clips or the flanges thereof more or less beyond the edge of the top sections to conform or adjust to the particular hood to 35 which the lining is being applied and to provide for variations in the hoods and in the linings. As shown the clips 19 are provided with slots 24 for receiving the shank of a bolt 25 which bolt extends through the lining, 40 and a nut 26 threads on the bolt against the outer or lower face of the lining or an interposed washer.

The sections 17, 18 of the lining are provided with means at their meeting edges for 45 detachably hinging them together, this means being here shown as fasteners including leaves 28, 29 secured respectively to the sections at their meeting edges, one leaf 28 being formed with a slot 28^a and the other 29 with a 50 pivoted hook or cam lever 30 for entering the slot 28^a, and after entering the slot clamping downwardly onto the leaf 29 to which said lever 30 is attached. This fastening means permits the side sections 18 to be readily detached when desired and also permits it to 55 hinge with the side section 6 of the hood. It will be understood that in the warmer months, the side sections of the lining are removed in order to uncover the louvers or slots 60 formed in the side sections of the hoods.

The side sections 18 of the lining are also provided with means for securing them at their lower edges to the lower edges of the side sections of the hood, this means being 65 here shown as spring actuated hook 31 or

hooks carried at the lower ends of coil springs 32, the other ends of which are secured to the side sections of the lining. In Figure 4 each of the top sections is shown as abutting at its lower edges at 33 against the side of a projected hollow rib 34 along the lower edge of the top sections and as lying behind upwardly extending leaves or flanges 35 inserted between the leaf forming part of the hinge 8 and the hood section 5. Each of the top sections 17 of the lining is sometimes provided with leaves or projecting flanges 36 at their lower edges for entering behind a bead 37 on the inner sides of the outer or lower edges of the top sections 5 of some hoods. Thus each top section of the lining is supported at its opposite edges independently of the side section of the lining.

In operation, the top section of the lining is first applied by hooking the lower edge 85 thereof behind the flange 35 or by hooking the leaves 36 behind the bead 37 at the outer edge of the top section of the hood and securing the clips 19 to the flanges 13 or 15 and thereafter the side sections 16 of the lining are attached by engaging the levers 30 of the detachable fastening members at the meeting edges of the sections of the lining and by hooking the spring pressed hooks 31 under the lower edges of the side section of the hood. 95

Owing to the construction of the fastening means for securing the lining in position, the lining is readily adaptable to standard automobile hoods.

In addition, it will be noted that in the 100 present lining only one of the sections is directly supported from the hood. In installing the lining the upper section is clipped onto the upper section of the hood, but instead of attaching the bottom section of the 105 lining directly to the hood said bottom section is hooked onto the previously installed upper section of lining. In view of the fact that it may sometimes be desirable to remove the bottom sections the means for suspending the bottom section from the top section are such that said bottom section is only detachably suspended from the upper section so that, in warm weather, the bottom section 110 may simply be unhooked at its upper edge from the bottom edge of the upper section. This not only facilitates installment and removal of the bottom section but it also eliminates the provision of fastening means on the hood itself so far as the bottom section 115 of the lining is concerned.

What I claim is:

1. The combination with an automobile hood having top and side sections, of a lining 125 comprising sections underlying the sections of the hood, the sections of the lining being provided with means secured to each of their meeting edges at the side of the hood for detachably securing them together independently of said hood sections, and with means 130

- at their upper and lower edges for securing the lining sections to the hood sections.
2. The combination with an automobile hood having top sections and side sections hinged to the top sections, of a lining comprising sections underlying the hood sections respectively, the sections of the lining being provided with means for detachably hinging them together at their meeting edges and with means remote from the meeting edges for securing them to the hood sections.
3. The combination with an automobile hood having top sections hinged at their top edges, such sections being formed with flanges on their inner sides at their hinged edges, of a lining for the hood, including a body and clips adjustably secured thereto, said clips having flanges at the edge of the body for coacting with the hood section flanges for attaching the lining to the hood, each clip being connected to the body by a sliding connection, means for tightening the clip to the body to increase or decrease the amount of projection of the clip flanges, and means for detachably securing the lower edge of the body remote from the clips to the edge of the hood.
4. The combination with an automobile hood having top sections, and side sections hinged to the top sections, of a lining comprising top and side sections, each top section having means for detachably securing it to the overlying top section of the hood, and each side section of the lining having means at its lower edge for detachably securing it to the contiguous side section of the hood, the lining sections having fasteners for hinging and detachably securing them together at their meeting edges.
5. An insulating lining for application to motor vehicle hoods, comprising a pair or more of sheet sections of heat insulating material, hinge connections between the adjacent edges of said sections for suspending one of said sections from the other independently of the hood, and devices carried by said sections and cooperative with the hood for detachably securing the sections in position adjacent the inner surface of the hood.
6. An insulating lining for application to motor vehicle hoods, comprising a sheet of heat insulating material and devices fastened to an edge of said sheet cooperative with the hood for detachably securing the sheet in position adjacent the inner surface of the hood, and separate fastening means secured to said sheet for suspending a second sheet of heat insulating material therefrom independently of the hood.
7. An insulating lining for application to motor vehicle hoods, comprising a sheet of heat insulating material, devices fastened to the upper and lower edges of said sheet and cooperative with the hood for detachably securing the sheet in position adjacent the in-

ner surface of the hood and separate securing elements attached to the lower edge of said sheet for detachably securing a second sheet of heat insulating material.

In testimony whereof, I have hereunto signed my name at Auburn, in the county of Cayuga, and State of New York, this 28th day of March, 1925.

ROBERT J. STEPHENSON.
